his ATTORNEY.

UNITED STATES PATENT OFFICE.

HENRY L. F. TREBERT, OF WEST BLOOMFIELD, NEW YORK, ASSIGNOR TO TREBERT AIRPLANE MOTOR COMPANY, INC., OF PENN YAN, NEW YORK, A CORPORATION OF NEW YORK.

PISTON HEAD.

1,412,427.

Specification of Letters Patent. Patented Apr. 11, 1922.

Original application filed August 27, 1917, Serial No. 188,342. Divided and this application filed August 1, 1921. Serial No. 488,796.

To all whom it may concern:

Be it known that I, HENRY L. F. TREBERT, of West Bloomfield, in the county of Ontario and State of New York, have invented certain new and useful Improvements in Piston Heads; and I do hereby declare the following to be a full, clear, and exact description of the same, reference being had to the accompanying drawings, forming a part of this specification, and to the reference numerals marked thereon.

My present invention relates to engines, being particularly useful in connection with internal combustion engines, and it has for its object to provide an improved piston head for such engines provided with a simple and serviceable means for insuring a uniform application of lubricating oil to the cylinder walls and in proper quantity. To these and other ends the invention consists in certain improvements and combinations of parts, all as will be hereinafter more fully described, the novel features being pointed out in the claims at the end of the specification.

In the drawings:

Figure 1 is a vertical central section through a fragment of an engine cylinder showing in similar section a piston head constructed in accordance with and illustrating one embodiment of my invention, and

Figure 2 is a bottom view of the piston taken in horizontal section through the cylinder.

Similar reference numerals throughout the several views indicate the same parts.

My present improvements are particularly applicable to rotary engines of the type shown in my pending application Serial No. 188,342, filed August 27, 1917, of which this is a division. Such engines embody cylinders having their axes radial to the axis of rotation of the engine, and difficulties are ordinarily experienced in lubricating all parts of the engine, and the cylinder walls in particular, because of the centrifugal force acting upon the oil within the crank case. The more usual tendency is for an excess of oil to be thrown toward the head of the cylinder forcing itself past the pistons and clogging the valve in the head and being wasted.

Referring more particularly to the drawings, 1 indicates an air cooled cylinder casting, 2 the cylinder wall or lining, 3 the cylinder head and 4 the valve cage and seat. Reciprocating in the cylinder is a piston head 5 having the usual central hub or boss 6 for the attachment of the connecting rod, except that in the type of engine shown there is no wristpin, the connecting rod being rigidly attached to the piston. The shank of such connecting rod is indicated in the present embodiment at 7. Its upper end is cylindrical as at 8 and fits into the hub 6 or boss 6 against which an enlargement or shoulder 9 below the cylindrical portion 8 abuts on the under side of the piston. A reduced threaded extension 10 above the portion 8 receives a nut 11 and washer 12 that are screwed down against the upper or outer side of the piston to secure it to the connecting rod. Below the shoulder 9 is a further enlargement in the form of an annular shoulder or collar 13 hereinafter referred to.

The piston skirt 14 contains the usual rings 15 and at its lower edge is formed with an annular groove or channel 16 forming a seat, the bottom wall of which is inclined in a direction toward the base of the cylinder as shown. In this seat I place an absorbent ring 17 preferably of felt or similar material. This ring is engaged by the peripheral edge of a perforated disk or diaphragm 18 that is dished or sprung outwardly at its center toward the base of the cylinder and there rests against the shoulder 13 by which it is retained. This diaphragm is preferably applied under tension, that is it is sprung slightly by the application of the cylinder head over it in assembling the parts so that the edge of the diaphragm bites into the ring 17 and securely retains it.

In operation the ring 17 acts as a wiper traversing the cylinder wall and spreading the oil evenly and preventing an excess thereof from working past the piston. The disk or diaphragm 18 aside from its function of merely retaining the ring 17 and resiliently spreading it into contact with the cylinder wall acts as a deflector that receives the oil thrown from the crank and directs it radially toward the ring 17 at all points

because of the centrifugal action and the inclination of the diaphragm itself.

I claim as my invention:

1. In a piston head for internal combustion engines, the combination with a piston skirt having an annular seat therein at its lower edge, of an absorbent wiper ring occupying the seat for contact with the cylinder walls.
- 10 2. In a piston head for internal combustion engines, the combination with a piston skirt having an annular seat therein at its lower edge, of an absorbent wiper ring occupying the seat for contact with the cylinder walls, and means mounted independently of the skirt for pressing the ring against the seat and cylinder walls.
- 15 3. In a piston head for internal combustion engines, the combination with a piston skirt having an annular seat therein at its lower edge, of an absorbent wiper ring occupying the seat for contact with the cylinder walls, and means mounted independently of the skirt for pressing the ring against the seat and cylinder walls.

skirt having an annular seat therein at its 20 lower edge, of an absorbent wiper ring occupying the seat for contact with the cylinder walls, and means mounted independently of the skirt for pressing the ring against the seat and cylinder walls, said means comprising a diaphragm secured centrally of the piston head and adapted to direct oil to the ring.

4. In a piston head for internal combustion engines, the combination with a piston 30 skirt having an annular seat therein at its lower edge, of an absorbent wiper ring occupying the seat for contact with the cylinder walls, and means for deflecting oil from the direction of the center of the piston and its 35 cylinder to said ring.

HENRY L. F. TREBERT.
